DESIGN FOR A DRESS

Mary Mullen, Philadelphia, Pa., assignor to Rosenau Bros. Inc., Philadelphia, Pa., a corporation of Pennsylvania

Application May 6, 1936, Serial No. 62,497

Term of patent 3½ years

To all whom it may concern:

Be it known that I, Mary Mullen, a citizen of the United States, residing at Philadelphia, in the county of Philadelphia and State of Pennsylvania, have invented a new, original, and ornamental Design for a Dress, of which the following is a specification, reference being had to the accompanying drawing, forming part thereof.

Figure 1 represents a front elevational view of the dress embodying the design.

Figure 2 represents a rear elevational view of the dress shown in Fig. 1.

Figure 3 represents a fragmentary perspective view of the front shoulder portion of the dress shown in Fig. 1.

The characteristic feature of the design resides in the combination on a dress of a plurality of floral elements extending throughout the length of the front panel at a side of the center line thereof, gathered sleeves, stripe-like elements at the top of the sleeves, yokes terminating at the front substantially below the collar, and the series of vertical pleats depending from each front yoke, as shown.

I claim:

The ornamental design for a dress as shown and described.

In testimony whereof I have hereunto set my hand.

MARY MULLEN.
